UNITED STATES PATENT OFFICE.

AMCIAH T. McELHANEY, OF BRADYS BEND, PENNSYLVANIA.

RAIL-JOINT.

No. 807,851.

Specification of Letters Patent.

Patented Dec. 19, 1905.

Application filed September 9, 1905. Serial No. 277,724.

To all whom it may concern:

Be it known that I, AMCIAH T. McELHANEY, a citizen of the United States of America, residing at Bradys Bend, in the county of Armstrong and State of Pennsylvania, have invented 5 certain new and useful Improvements in Rail-Joints, of which the following is a specification, reference being had therein to the accompanying drawings.

10 This invention relates to certain new and useful improvements in rail-joints; and the invention has for its object to provide a novel form of rail support and fastener for securing the confronting ends of two sections of 15 rails together.

My improved rail-joint embodies a chair adapted to support the confronting ends of the rails. The one side of the chair is formed at an angle to the opposite side, whereby a 20 wedge-shaped fish-bar may be inserted in the chair to clamp the rails therein. Novel means is employed for locking the wedge-shaped fish-bar within the chair, also means for preventing longitudinal displacement of the rails 25 supported by the chair.

The detail construction of my improved rail-joint will be hereinafter more fully described, and reference will now be had to the drawings accompanying this application, 30 wherein I have illustrated the essential features of the invention.

Figure 1 is a perspective view of my improved rail-joint. Fig. 2 is a perspective view of the chair employed in connection with 35 a joint. Fig. 3 is a similar view of a fish-bar. Fig. 4 is a cross-sectional view of the joint, illustrating the means employed for fastening the fish-bar within the chair. Fig. 4^a is an end view of the fish-bar. Fig. 5 is a 40 horizontal sectional view of my improved joint, and Fig. 6 is a plan view of the fish-bar.

Like numerals of reference designate corresponding parts throughout the several views of the drawings.

45 To put my invention into practice, I employ a chair 1, consisting of a base-plate 2, the one side of which is provided with an integral fish-bar 3 of a conventional form capable of embracing the one side of the ordinary 50 type of rail. Between the flanged portion 4 of the fish-bar 3 and the base of the chair are formed inwardly-extending lugs 5 5, these lugs being preferably located near the center of the chair. The lugs are adapted to prevent 55 longitudinal displacement of the rail support-

ed by the chair, and to accomplish this I provide the one side of the base-flanges 6 6 of the rails 7 7 with recesses 8 8, adapted to receive the lugs 5 5 of the chair and prevent the rails from becoming longitudinally displaced, but at 60 the same time permitting sufficient movement for expansion and contraction of said rails. The opposite side of the base-plate 2 of the chair is provided with an upwardly-extending angularly-disposed side wall 9, which is formed 65 at an oblique angle to the base of the chair, thus providing a tapering seat within the chair for the rails 7 7 and a fish-bar 10, which will be presently described. The upper edge 11 of the side wall 9 is flanged inwardly at 70 substantially right angles to the side wall 9. Adjacent to each end of the upper edge 11 of the side wall 9 is formed a groove 12, which terminates in an angularly-disposed opening 14, formed in the side wall 9 of the chair 1. 75 The object of these openings will be presently described. At the juncture of the side wall 9 and the base-plate 2 of the chair is formed a longitudinally-disposed groove 15, which is adapted to limit the movement of the fish-bar 80 10, which is mounted in the chair.

The fish-bar employed in connection with the chair and rails just described consists of a web portion 16 and a flanged portion 17, which carries an enlarged tapering rib 18. 85 The formation of the rib 18 provides a depending V-shaped flange 19, adapted to engage in the groove 15 of the chair 1. The upper edge of the rib 18 adjacent to its ends is provided with recesses 20 20, these recesses 90 being of a greater width than the grooves 12 of the chair.

When two rails are to be secured within the chair 1, the rails are placed therein prior to placing the fish-bar 10 within the chair. In 95 Fig. 4 of the drawings I have illustrated the manner in which the rails are locked within the chair and prevented from becoming longitudinally displaced, it being obvious that the lugs 5 5 of the chair engage the base-flanges 6 6 of the rails. In order to retain the rails within the chair, the fish-bar 10 is placed in the chair between the side wall 9 and the rails 7 7. To accomplish this, it is necessary to slide the fish-bar 10 into the chair at one 100 end thereof, and as the side wall 9 is at an angle to the longitudinal base of the chair the rib 18 of the fish-bar 10 will impinge between the rails 7 7 and the side wall 9. In 105 the operation of placing the fish-bar in posi- 110

tion the flange 19 slides in the longitudinally-disposed groove 15 of the chair and engages the base-flanges of the rails 7 7. It will be observed that when the fish-bar is placed in position the upper edge of the rib 18 engages the underneath face of the upper edge 11 of the side wall 9, and as the face of the rib 18 has recesses formed therein these recesses will at one time coincide with the grooves 12 of the side wall, forming openings in alinement with the openings 14 of the chair 1. Wedge-shaped keys 21 are then employed for locking the fish-bar 10 within the chair, these keys being passed upwardly through the openings 14 of the chair until they engage in the recesses 20 of the fish-bar and the grooves 12 of the chair, at which time the upper ends of the keys are bent upon the upper edge 11 of the side wall 9, as designated at 22 in Figs. 1 and 4 of the drawings. In this manner it will be impossible for the fish-bar to become detached from the chair, and the web portion 16 and flanged portion 17 of the fish-bar will firmly retain the rails 7 7 in engagement with the fish-bar 3 of the chair, at the same time permitting sufficient movement of the rails, owing to the expansion and contraction of the material from which they are formed. As the fish-bar 10 is tapering in form and a seat is formed in connection with the chair to accommodate the same, it will be possible to adjust the bar within the chair in case the same should become worn by the continual stress exerted upon the same by the rolling-stock passing over the rails, and when any adjustment of the bar is to be made it will not be necessary to remove the keys 21 on account of sufficient movement of the bar being permitted by the recesses 20 being of a greater width than the grooves 12 of the chair 1.

The chair and fish-bar which constitute my improved joint are preferably made of strong and durable material, such as steel, and the simplicity of construction permits of the same

being manufactured at a comparatively small 45 cost.

It will be noted that various changes in the form, proportion, and minor details of construction may be resorted to without departing from the spirit and scope of the invention. 50

What I claim, and desire to secure by Letters Patent, is—

1. In a rail-joint, the combination with two sections of rails, of a chair adapted to support said rails, a fish-bar carried by one side of said chair, lugs carried adjacent to said fish-bar and adapted to engage said rails, a side wall carried by the opposite side of said chair, said side wall having openings formed therein, said chair having a groove formed therein, a wedge-shaped fish-bar adapted to engage said side wall and said rails, a rib carried by said fish-bar and adapted to engage in the groove of said chair, keys passing through said side wall and engaging said fish-bar, means to lock said 65 keys in said side wall, substantially as described.

2. In a rail-joint, a chair comprising a base-plate having at one side edge an integral fish-plate adapted to engage rails seated on the 70 base-plate, and at its other side edge having a fish-plate of integral form in cross-section embodying an outwardly-inclined side wall and an inwardly-inclined side wall, a base-plate having a groove adjacent the base of said outwardly-inclined side wall, a fish-plate adapted to fit between rails seated on the base-plate and said side walls, and having a rib extending the length of said plate and seated in the 75 groove, said rib engaging the edge of the rail-base, and means for securing said fish-plate to the said angular walls.

In testimony whereof I affix my signature in the presence of two witnesses.

AMCIAH T. McELHANEY.
